CLAIM

The ornamental design for a perfume bottle, as shown and described.

DESCRIPTION

FIG. 1 is a front perspective view of a perfume bottle showing my new design;
 FIG. 2 is a front view thereof;
 FIG. 3 is a back view thereof;
 FIG. 4 is a left side view thereof;
 FIG. 5 is a right side view thereof;
 FIG. 6 is a top view thereof; and,
 FIG. 7 is a bottom view thereof.

The broken line showing of the nozzle and atomizer in the drawings shows unclaimed subject matter.
